[57] CLAIM

The ornamental design for a top rail for a loader bucket, as shown and described.

DESCRIPTION

FIG. 1 is a perspective view of a top rail for a loader bucket, showing our new design;

FIG. 2 is an enlarged end elevational view thereof;

FIG. 3 is a front elevational view thereof;

FIG. 4 is a top plan view thereof;

FIG. 5 is a rear elevational view thereof;

FIG. 6 is a bottom plan view thereof; and;

FIG. 7 is a perspective view of a second embodiment thereof.

The dotted line showing is for illustrative purposes only, and forms no part of the claimed design.
